BRUSH DRILLING MACHINE

Leonard B. Terhune, Newark, N. J., assignor to
 Dupont Viscoloid Company, Wilmington, Del.,
 a corporation of Delaware

Original application May 23 1929, Serial No.
 365,495, now Patent No. 1,937,101, dated No-
 vember 28 1933. Divided and this application
 October 25, 1933, Serial No. 695,130

12 Claims. (Cl. 144—94)

My invention relates particularly to a mechanism for drilling holes in brush blanks, in the manufacture of brushes generally, and which has application to the manufacture of brushes of any desired type.

This application is a division of my application upon Drilling and inserting mechanism for brush machines, Serial No. 365,495, filed May 23, 1929.

10 The object of my invention is to provide a mechanism for drilling holes in brush blanks in all types of brushes, for example, toothbrushes, hand-scrub brushes, etc. The object of my invention is particularly to provide a drilling machine which is applicable to machines in which the brush blanks are designed to be held or moved in any manner, although the machine made in accordance with my invention is especially applicable for use in connection with the machine disclosed in my application entitled Brush holders for brush making machines, Serial No. 338,978, filed February 11, 1929, Patent No. 1,913,863, granted June 13, 1933, and my application Serial No. 365,495, Patent No. 1,937,101, granted November 28, 1933, above referred to. The object of my invention is to provide, also, a mechanism comprising operating parts which include multiple drilling devices for use, if desired, in connection with a single brush holder mechanism, such as that shown in my applications above referred to, and which, nevertheless, is embodied in a unitary mechanism. Again, the object of my invention is especially to provide a mechanism for operating the drilling devices which is not only applicable to many different methods of holding and moving the brush blanks, but which is compact and which, therefore, may be constructed and maintained at a minimum of expense and with a minimum amount of labor. I have accomplished this end particularly by reason of the fact that the drilling mechanism is operated from a cam shaft which is located substantially centrally in the machine. This is of particular importance, also, by reason of the fact that this cam shaft may also be the main shaft operating the brush holder holding the blanks for cooperation with the drilling mechanism. Also, the object of my invention is to provide an interchangeable drill holding unit so that the same may be replaced by other similar units when repairs are needed, or when brushes of different types are desired to be manufactured, in which the placing of the holes in the brush blanks is sufficiently different to require a different location for the multiple drills used in the machine. This arrangement of

the parts also permits, as will be readily understood, the different parts of the mechanism to be removed without interfering with the operation of the remaining units which are contained in the machine while the others are being repaired, replaced, etc. Further objects of my invention will appear from the detailed description of the same hereinafter.

While my invention is capable of embodiment in many different forms, for the purpose of illustration I have shown only one embodiment of my invention in the accompanying drawings, in which—

Fig. 1 is a plan view of a drilling machine made in accordance with my invention; 15
 Fig. 2 is a side elevation of the same;
 Fig. 3 is a front view of the same;
 Fig. 4 is a horizontal section of the same;
 Fig. 5 is a rear elevation partly in section;
 Fig. 6 is a transverse vertical section showing 20 the nozzle unit;

Fig. 7 is a vertical section of the same taken at right angles to the section shown in Fig. 6;

Fig. 8 is a detail perspective view of the needle bar and needle; 25

Fig. 9 is a fragmentary perspective view enlarged, showing the picker and picker knife operating bars;

Fig. 10 is an enlarged detail in section showing 30 the arrangement of the picker and picker knife in the removable unit containing the same;

Fig. 11 is an enlarged horizontal section showing the picker and picker knife;

Fig. 12 is an enlarged fragmentary perspective view showing the wire from which the anchors 35 are made and the rolls for feeding same;

Fig. 13 is a fragmental detail section of a brush blank showing the bristles as carried in one of the holes and held therein by the anchor made from the wire referred to; 40

Fig. 14 is a vertical section through the brush holder mechanism; and

Fig. 15 is an elevation of a spring plunger used as a pawl in connection therewith. 45

In the machine which I have used, by way of illustration of my invention, the arrangement is applicable for use in the manufacture of brushes of any desired type, or kind, but is especially applicable to the manufacture of toothbrushes, by way of example. In this machine I have shown a main operating shaft 1 carried in any suitable bearings 2 supported on a main frame 3, and secured thereto by bolts 3a, carried on a base 4, which is shown in Fig. 2 with a broken line at the part thereof which may be 50 55

extended so as to form a supporting base for any desired type of brush holder mechanism, as, for example, that shown in my application hereinabove referred to. It will be understood that the shaft 1 may, and preferably is, the same shaft as the main shaft contained in the said brush holder mechanism in my application as referred to above, said shaft being provided in the said brush holder mechanism with any desired journal bearings for this end of the said shaft. This main shaft 1 may be driven from any suitable source of power, as, for example, by means of a pulley 5 tightly mounted on the shaft 1, carrying a band 6 on its periphery designed to be driven from any suitable source of power, as, for example, an electric motor, etc. Mounted on said pulley 5 there is a ring gear 7 which drives a series of six intermediate gears 8, 9, 10, 11, 12, and 13, which are mounted on stud shafts 14 carried in a removable spider 15 adapted to be secured to the journal bearing 2 by means of screws 16. These gears 8, 9, 10, 11, 12, and 13 are provided for the operation of six drills 17, 18, 19, 20, 21, and 22, all of which are driven by a suitable train of gearing in each instance, the gearing for these six drills being exactly the same for driving each particular drill. Accordingly, only one of these trains of gearing will be described in detail. The intermediate gear 8 has secured thereto a larger gear 23 which in turn meshes with a gear 24 attached to a drill spindle 24a carrying the drill 17 rotating in a bushing 25 in the said spider 15, and provided with a drill chuck 26 of any desired type on the spindle 24a. The drill spindle 24a with the attached gear 24 is arranged to be longitudinally slidably manually out of engagement with the brush blank by means of a slide 26a having a thumb piece 26b for the movement of the same, and a slot 26c for receiving a screw 26d which is tightened in place during the time when the drill 17 is to be operated but which will be loosened when it is desired to throw the particular drill out of operation. A recess 26e in the slide 26a cooperates with a spring-pressed ball 26f in the retracted position to hold the drill in the inoperative position for repairs, replacements, etc. The slide 26a is connected to the spindle 24a by means of a yoke 26g located in an annular recess 26h on the face of the gear 24.

It will be understood that the machine is equipped, not only with multiple drills as above described, but also with duplicate inserting mechanisms for inserting the bristles into the brush blanks, although only one of such inserting mechanism will be described in detail as both of them are constructed and operated in exactly the same manner, except that these two inserting mechanisms are constructed as right- and left-hand devices, respectively, as they are located on opposite sides of the machine.

The shaft 1 on the other side of the spider 15 from the gearing just described, carries a cam wheel 27 having a cam groove 28 in its face in which there is designed to be moved a roller 29 for operating the picker. This roller 29 is carried on a stud shaft 30 passing into a picker bar 31 which is guided for transverse movement within a U-shaped picker knife bar 32. Both the picker bar 31 and the picker knife bar 32 are arranged to reciprocate in a groove 33 in the main frame 3. At its end the picker bar 31 has a right angle extension 34 which rests within a recess 35 in the picker 36, which reciprocates transversely of the machine in a groove 37 located in a removable bar 38 adapted to be secured to

the main frame by means of screws 39. A cover plate 40 fits over the top and side of said picker 36 and is secured to said bar by means of screws 41. It will be noted that the picker 36 has a vertical recess 42 to enable it to pick a charge of bristles from a bristle feeding passageway 43 provided with a continuously fed supply of bristles 44 supplied thereto from any suitable bristle feeding mechanism, as, for example, the mechanism as disclosed in my application upon Bristle magazines for brush making machines, Serial No. 338,979, filed February 11, 1929, it being understood that on the opposite side of the machine there is a duplicate of this bristle feeding mechanism, except that the two feeding mechanisms are arranged in the right and left hand positions, respectively. Also, within the picker 36 there is provided a picker knife or a separator bar 45 having a pointed edge 46 at its extreme end to separate the charge of bristles in the recess 42 from the bristles 44 carried in the passageway 43 and hold them therein until they are carried by the simultaneous movement of the picker 36 and the picker knife 45 to a bristle inserting nozzle 47, it being understood that another such nozzle 47a, with cooperating parts, is located on the opposite side of the machine. This picker knife 45 is moved by means of a right angle extension 48 resting within a recess 49 in the side of the picker knife 45, which right angle extension is carried upon the picker knife bar 32. This picker knife bar 32 is moved by means of a cam roller 50 which operates within a cam groove 51 in the face of a cam wheel 53 carried on the shaft 1 adjacent to the cam wheel 27.

In order to feed to the mechanism a wire 54 from which there is to be cut flat anchors 55, this wire 54 is supplied to the machine by means of two feed rollers 56 and 57, the former being carried in bearings 58 secured to the main frame 40 and the latter in a sliding carriage 59 pressed downwardly by springs 60 on rods 61 having nuts 62 thereon for the adjustment of compression of said springs, which rods project upwardly from the main frame. The feed roller 56 is operated by means of a ratchet wheel 63 secured thereto, and which is driven by means of a spring-pressed pawl 64 carried in an arm 65 pivoted on the shaft carrying the feed roller 56. This arm 65 has on its outer end a roller 66 which is held against an outer cam periphery 67 of the cam wheel 27 by means of a spring 68 extending from the arm 65 to the spider 15. In this way the wire 54 is fed across a recess 69 in which there is arranged to reciprocate a punch 70, secured in a groove in the face of a block 71, carried in a vertically reciprocating bar 72 which is arranged to reciprocate in the main frame, a tapered pin 73 being provided for tightly securing said block 71 within the bar 72. This bar 72 is reciprocated by means of a pin 74 extending laterally therefrom and thence into a slot 75 in a lever 76 carried on a fixed pivot 77 by the main frame, which lever 76 has a roller 78 adapted to be moved by a cam groove 65-79 in the front face of the cam wheel 53. Like mechanism is provided on the other side of the machine for operating the punch on that side of the same, the same roller 78 being provided for this purpose and having a pin extension 78a, 70 on which said roller is pivoted for cooperating with a slot 78b in the said lever on the other side of the machine.

In order to complete the insertion of the bristles with the anchor into a brush blank 80, 75

which is supported on any suitable brush blank holder 81, such, for example, as that shown in my application Serial No. 338,978 above referred to, I have provided a needle operating mechanism. This is comprised of a cam wheel 82 which is also mounted tight on the shaft 1, and which has a cam groove 83 on its periphery for the operation of a roller 84 on a needle bar 85. This needle bar 85 operates in a movable channel-shaped box 86 which is secured to the main frame 3 by means of screws 87 and 88 which pass through ears extending from the said channel-shaped box 86. This channel-shaped box 86 is, furthermore, arranged to support in place the nozzles 47 and 47a to which the latter is secured by screws 86a. A cover plate 86b is also provided over the rear end of the channel-shaped box 86 to which it is attached by screws 86c. A needle 89 is secured in the top of a projection 90 on the bar 85 by means of a clamping plate 91 having screws 92 to hold the same in place thereon, a thumb recess 93 being provided at one side thereof to permit the needle 89 to be grasped for the adjustment of the same longitudinally of the bar 85. This bar 85 is so located with regard to the nozzle 47 as to adequately support the needle 89 without danger of bending or breaking the same and without requiring the soldering thereto of any bracing or holding member at the rear of the same. This is accomplished in the following manner: The nozzle 47 is divided into a lower grooved portion 94 having a groove 95 therein for carrying the said needle, and an upper portion 96 for covering the same, both portions being cut out to provide an opening 97 extending entirely through the nozzle vertically and in such a position as to support one half of the width of the needle, as shown in Fig. 4, when the needle is in retracted position. This provides an adequate support for the needle, by supporting one half of the width of the same during the initial travel of the needle when no great strength is required therein, and when the load is taken up by the needle the recess 97 is almost entirely closed by the bar 85 and thereby leaves only a negligible portion of the needle unsupported at this period of the operation. The movement of the needle 89 is thus coordinated with the movements of the picker mechanism, and the anchor punch mechanism so that the said needle, when it reaches the aperture 69, will pick up the anchor 55 and the tuft of bristles in advance of the same, thus folding the bristles and forcing the tuft of bristles with the anchor between the fold out through the end of the nozzle 47 into the brush blank 80 by causing the anchor 55 to cut slightly into the sides of the drilled hole of the brush blank until the tuft of bristles is thus securely anchored at the bottom of the drilled hole. It will be understood that when the tuft of bristles with the anchor 55 carried in the rear thereof, reaches the position where it is about to enter the brush blank, the brush blank 80 will already have been moved up to this point by any suitable means or mechanism, such, for example, as that shown in my application Serial No. 338,978, and that after the insertion of the tuft has been completed in this manner the brush blank will again be moved to withdraw the bristles from the nozzle 47 and to the next proper position for the insertion of the next tuft therein by said mechanism.

It will be understood that the two inserting nozzles 47 and 47a may be operated simulta-

neously for the insertion of bristles in the respective brush blanks located opposite thereto, or, if desired, one of them may be removed at any time without interrupting the operation of the other, thereby continuing the operation of the brush blank holder, notwithstanding the removal of one set of mechanisms. When it is desired to remove the inserting mechanism this is readily accomplished merely by removing the screws 87 and 88 and then pivoting the unit upwardly on the roller 84 until the adjacent parts are cleared.

Likewise, it will be understood that the picker unit may be readily removed by removing the screws 39 and lifting the same away from the right angle extensions 34 and 48 so that a new picker mechanism may be inserted, and so that, if desired, the operation of the machine may be continued without interruption as to the remaining picker mechanism in the apparatus. As above noted, there are provided in the machine two sets of drills 17, 18 and 19 and 20, 21, and 22, which are provided for preparing the holes in the brush blanks for the nozzles 47a and 47 respectively. The last drill of the particular set, just before its particular nozzle, may, if desired, be provided with a reamer. However, the main purpose of providing the plurality of drills, all of which are designed to drill the same holes three times in succession for the particular nozzle, is to prevent stoppage and interruptions in the operation of the machine, owing to the fact that one of the greatest causes in the ineffective operation of brush making machines is the inaccurate and ineffective preparation of the holes so as to make them of exactly the same size and shape for the receipt of the tufts of bristles to be inserted therein. It will be readily understood that where each of the holes is thus drilled three times, or drilled twice and reamed once the holes will acquire a uniform size and shape and thus greatly conduce to the effective and uninterrupted operation of the machine. Furthermore, it will be realized, nevertheless, that, if desired, one or two of the group of three drilling operations may be dispensed with, either voluntarily or due to breakages therein, without necessarily preventing for the time being the continued operation of the machine as a whole. Besides, if more than two of the drills of a set are thrown out of action, accidentally or otherwise, the inserting mechanism which is used to cooperate therewith may be thrown out of operation so as to allow the remainder of the machine to operate, and even the inserting mechanism of one set and the series of drills of the other set may be simultaneously out of operation so that the remaining inserting and drilling mechanisms may be used for continued operation without shutting down the machine.

Thus, it will be seen that the multiple drilling and inserting mechanisms enable the machine to be maintained in operation without the disadvantageous interruptions, and high cost of maintenance, that have been prevalent in brush making machines, which have been the cause of high cost of production in the manufacture of brushes to a very large extent. Furthermore, the maintenance of the machine is greatly facilitated by the compactness of the construction involving the use of a central operating shaft for operating the drilling and inserting mechanisms by cams carried thereon.

Figs. 14 and 15 show the brush holder mechanism adapted to be used in connection with the

applicant's invention, which is the same as that shown in the applicant's co-pending application upon Brush holders for brush making machines, Ser. No. 338,978, filed February 11, 1929, Pat. No. 1,913,863, granted June 13, 1933. In the said brush holder mechanism I have shown a main shaft 101 carried in a frame 102, which shaft has connected thereto means for driving the same at any desired speed from any suitable source of power. Surrounding the shaft 101 there is provided an annular disk-shaped brush blank holder 105 adapted to receive a succession of brush blanks 106, as, for example, tooth brush blanks, which may be continuously fed thereto by hand, or otherwise, at the periphery of the holder, the arrangement being such that the completed brushes, after drilling and filling, are continually removed from the holder. As will be noted, each of the brush blanks 106 occupies a different position with regard to the center of the disk 105, each being located on its own individual radius thereon. Each of the brush blanks 106 is supported in the holder 105 upon a movable carriage 109 which is provided with projections 109a, 109b to fit around the ends of and tightly hold the brush blank in place while being operated on for drilling or filling. The carriage 109 is supported by two links 110 and 111, by means of a ball and socket joint 112 and pivot 113 allowing a certain amount of lateral play between the lever 111 and said pivot 113 to secure the accurate positioning of the carriage 109. The positioning of the carriage 109 is accomplished by means of a pin 114 projecting from the frame, and having a point 115 with a very acute angle at the point of the pin 114 to accurately fit within each one of a series of countersinks 116 of substantially the same shape on the face of the brush blank 106, in the rear face of the carriage 109, one of said countersinks 116 being provided for each of the holes to be drilled and filled in the brush blank 106. This pin 114 is normally held in retracted position by a spring 115a, cooperating with a shoulder 15b thereon, and the pin is moved forwardly by a plunger 115c thereon, having an interposed spring 115d, which is moved by an adjusting pin 115e contacting with said plunger. It is by this means that the brush holder 109 is pushed forward to the drill 115f or instead the filling nozzle. A spring-pressed plunger 117 having an obtusely shaped point 118, fits also in a similar series of countersinks 119 for roughly holding the carriage in its position between the intervals of accurate adjustment by the point 115 and while the blank on the carriage is not being operated on for drilling and filling. Said plunger 117 is supported in a sleeve 120 forming a part of a sliding frame 123 to which levers 110 and 112 are secured by pivots 121 and 122, which frame is carried on a pin 124 projecting forwardly from the blank holder 105. A spring retracted guiding rod 125, furthermore, is provided with a connecting pin 126, secured in an opening 127 in the sliding holder 120 for guiding and supporting the same. A spring 127a provides the plunger 117 with a light forward pressure at all times. The carriage 109 is brought into its initial position for the drilling or filling of the first hole thereof by means of a cam 128 which is secured to the hub of a counter shaft 128a, said cam 128 having a cam surface 129 for cooperating with a roller 130 on an arm 131 carried by a sleeve 132 which has a flange 133 engaging with yokes 134 on bell crank levers 135, which are pivoted to the main frame and carry yokes 136 having releasable

engagement with rollers 137 attached to the inner end of the carriage 109. The releasable movement referred to is due to the open yokes 136 in which the rollers 137 are received. This permits the disengagement of those of the blanks not being operated upon at any time so as to contribute to the maintenance of and the continued operation of the machine. It will be noted that a spring 138 located between the inner end of the sleeve 132 and the frame 102 keeps the roller 130 in contact with the cam 128. This cam 128 is moved by a ratchet wheel 139 on the shaft 128a, which in turn is moved by a pawl 140 on a lever arm 141, having a loose connection, by a link 142 to a reciprocating frame 143 supported by a sleeve 144 on the shaft 101 inside of the sleeve 132. A cam 145 on the main shaft 101 contacts with a roller 146 on the reciprocating frame 143 so as to move the same at the proper intervals, thereby rotating the cam 128 and moving the frame 143, 20 which carries the adjusting screws 115e so as to move the points 114 forwardly and in turn bring the brush holders 109 up to the drills and nozzles. This reciprocating frame 143 also has arms 147 for insuring the retraction of the guiding rods 25 125 to their initial position, thus definitely positioning the brush blank holders 109 initially.

In order to rotate the disk-shaped holder 105 from one row of holes to another, and from one blank to another, the latter carries a circular 30 rack 148, adapted to slidably interlock with the main frame 102, having teeth 149 corresponding to the movements from one row of holes to another and from one blank to another. As shown in Fig. 15, a spring pressed plunger 150 is provided for moving the rack 148, which plunger is carried on a ball crank lever 151 supported on a pivot 152 located on the main frame 102, the other end of which lever has a projection 153 adapted to be operated by two long projections 154 and 40 155 and four short projections 156, 157, 158, and 159 on the ratchet wheel 139.

While I have described my invention above in detail I wish it to be understood that many changes may be made therein without departing 45 from the spirit of the same.

I claim:

1. A brush drilling mechanism comprising a plurality of drills each having a spindle and a driving gear thereon, means for driving the same, 50 and a manually operated device for retracting any particular drill spindle with its gear when not in use.

2. A brush drilling mechanism comprising a plurality of drills each having a spindle and a 55 driving gear thereon, gears for driving the same, a manually operated device for retracting any particular drill spindle with its gear when not in use, means for driving said drills from a source of power, and a detachable spider on which said 60 multiple drills and gears are carried.

3. A brush drilling mechanism comprising a plurality of drills each having a spindle and a driving gear thereon, means for driving the same, and a device for retracting any particular drill 65 spindle with its gear when not in use.

4. A brush drilling mechanism comprising a plurality of drills each having a spindle and a driving gear thereon, gears for driving the same, a device for retracting any particular drill spindle 70 with its gear when not in use, means for driving said drills from a source of power, and a detachable spider on which said multiple drills and gears are carried.

5. A brush drilling mechanism comprising a 75

- frame, a plurality of drills each having a spindle and a driving gear thereon located on different radii of the frame, means, including a gear on the center of said radii, for driving the same, and a manually operated device for retracting any particular drill spindle with its gear when not in use.
6. A brush drilling mechanism comprising a frame, a plurality of drills each having a spindle and a driving gear thereon located on different radii of the frame, gears, including a gear on the center of said radii, for driving the same, a manually operated device for retracting any particular drill spindle with its gear when not in use, and means for driving said drills from a source of power, said frame comprising a detachable spider on which said multiple drills and gears are carried.
7. A brush drilling mechanism comprising a frame, a plurality of drills each having a spindle and a driving gear thereon located on different radii of the frame, means, including a gear on the center of said radii, for driving the same, and a device for retracting any particular drill spindle with its gear when not in use.
8. A brush drilling mechanism comprising a frame, a plurality of drills each having a spindle and a driving gear thereon located on different radii of the frame, gears, including a gear on the center of said radii, for driving the same, a device for retracting any particular drill spindle with its gear when not in use, and means for driving said drills from a source of power, said frame comprising a detachable spider on which said multiple drills and gears are carried.
9. A brush drilling mechanism comprising a frame, a plurality of drills each having a spindle and a driving gear thereon located on different
- radii of the frame, means, including a gear on the center of said radii and smaller gears inserted between said gear and the drills, for driving the same, and a manually operated device for retracting any particular drill spindle with its gear when not in use.
10. A brush drilling mechanism comprising a frame, a plurality of drills each having a spindle and a driving gear thereon located on different radii of the frame, gears, including a gear on the center of said radii and smaller gears inserted between said gear and the drills, for driving the same, a manually operated device for retracting any particular drill spindle with its gear when not in use, and means for driving said drills from a source of power, said frame comprising a detachable spider on which said multiple drills and gears are carried.
11. A brush drilling mechanism comprising a frame, a plurality of drills each having a spindle and a driving gear thereon located on different radii of the frame, means, including a gear on the center of said radii and smaller gears inserted between said gear and the drills, for driving the same, and a device for retracting any particular drill spindle with its gear when not in use.
12. A brush drilling mechanism comprising a frame, a plurality of drills each having a spindle and a driving gear thereon located on different radii of the frame, gears, including a gear on the center of said radii and smaller gears inserted between said gear and the drills, for driving the same, a device for retracting any particular drill spindle with its gear when not in use, and means for driving said drills from a source of power, said frame comprising a detachable spider on which said multiple drills and gears are carried.

LEONARD B. TERHUNE.
